UNITED STATES PATENT OFFICE.

GEORGE F. MINNIS, OF CHICAGO, ILLINOIS.

ANCHOR FOR WINDOW-WASHERS' BELTS.

1,250,202.

Specification of Letters Patent.

Patented Dec. 18, 1917.

Application filed March 12, 1917. Serial No. 154,086.

To all whom it may concern:

Be it known that I, GEORGE F. MINNIS, a citizen of the United States, residing at Chicago, in the county of Cook and State of Illinois, have invented certain new and useful Improvements in Anchors for Window-Washers' Belts, of which the following is a specification.

My invention relates to improvements in anchors and more particularly to an anchor for attachment to a stone or brick wall, the anchor head being arranged for engagement by the safety clasp of a window cleanser's harness.

One of the objects of my invention is to provide such an anchor for mounting upon the reveal of a window opening with the body part of the anchor extending through and into engagement with the second layer 20 of brick or stone.

Another object of my invention is the provision of such an anchor which may be firmly and rigidly locked in position, is not liable to be pulled out, and at all times retains a firm grip upon the wall even though the mortar in which it is embedded should become loose or cracked.

Still other and further objects will become readily apparent to those skilled in the art 30 from a consideration of the following description and drawings, wherein—

Figure 1 is a side elevation of a portion of a building adjacent the window casing showing my improved anchor in place.

Fig. 2 is a plan view of my improved anchor showing the manner of mounting the same in the wall.

Fig. 3 is a perspective view of the anchor.

Fig. 4 is a front elevation of an improved clip for engagement with the anchor.

Fig. 5 is a vertical sectional view through the clip shown in Fig. 4.

Fig. 6 is a side elevation of a portion of 45 a building showing a modified form of anchor in place.

Fig. 7 is a plan view of the modified form of anchor showing the manner of embedding the same in a wall, and

Fig. 8 is a perspective view of the anchor 50 illustrated in Figs. 6 and 7.

It is common practice for window cleaners when working outside of a building to wear a waist encircling belt to which a rope 55 is secured with its ends supplied with clips

for engagement with fastening devices secured to the wall of the building or to the window casing, at each side of the window. These anchoring devices must, of necessity, be amply strong to withstand the weight 60 of a man in the event the cleaner should lose his footing and slip over the window ledge. Beside the necessity of providing material of ample strength and size, it is also essential that such devices be firmly anchored in 65 the wall. In practice it is found desirable in many instances to position the anchor head on the reveal at each side of the window frame rather than on the outer face of the wall where they are more conspicuous 70 and somewhat more difficult for the cleaner to reach. This is particularly desirable in buildings faced with terra cotta and against which the anchors would stand out conspicuously and impair the neat smooth appearance of the structure.

In the two embodiments of my invention illustrated in the drawings I have provided an anchor, the head of which is arranged for presentation on the reveal formed between the outer face of the wall and window casing. The anchor is so arranged that it projects from this point within the wall past the embedded edge of the window casing and into engagement with the rear face of 85 the second tier of bricks.

Referring more particularly to the form of device illustrated in Figs. 1 to 3 inclusive, the numeral 10 indicates the vertically elongated head of an anchor adapted to overlie 90 the surface of the bricks in the reveal and from the outer face of which projects the vertically spaced apart lugs 11 with their enlarged heads 12 for engagement with the window washers safety clip indicated in 95 general by the numeral 13. From the central portion of the rear face of the head 10 I have extended a flat bar 14 tapering gradually from its widest portion adjacent the head to its end portion 15, the extreme end 100 being headed or enlarged vertically, as at 16, to overlie the rear edges of the second layer of brick or stone. The head is disposed at an angle to the adjacent portion of the bar so as to parallel the rear face of the 105 second layer of brick.

By referring to Fig. 2 of the drawings it will be evident that the bar 14 through its widest front portion extends from the head 10 in a sweeping curve indicated in general 110

by the numeral 17 to permit it to pass back of the embedded corner of a window casing 18. The rearwardly extending end portion 5 of the bar which is considerably narrower than the front portion is substantially straight and lies at an angle to the face of the wall to position the head 16 in the mortar 19 lying between the second layer of brick 20 and the third layer 21. The body 10 of the bar 14 lies in the mortar between the upper surfaces of brick 20—22—23 and the bottom surfaces of the course of bricks immediately thereabove. The head 16 is of a vertical width considerably greater than the 15 thickness of the mortar between two courses of bricks so that it overlies the rear edges of two adjacent courses of bricks in the second layer. The engagement between the headed end at the rear of the bar 14 and 20 the second layer of brick tends always to draw the brick 23 and the one immediately thereabove over against the window casing instead of pulling it outwardly as would be the case if the anchor extended straight in 25 from the outer face of the wall.

In Figs. 6 to 8, I have illustrated a modified form which the invention may take and in which the flat bar indicated in general by the numeral 30 extends straight backward 30 from the head 10 a distance sufficient to pass beyond the edge of the window casing 18 and then turns at right angles, as at 31, inwardly, the outer portion 32 being parallel with the face of the wall and at substantial 35 right angles to the inner portion 33 which extends a distance inwardly in the wall to position the head 16 on the end of the section 32, at the rear face of the second layer of bricks 20. This angled construction permits the mounting of an anchor on the reveal even should the window casing 18 project outwardly as indicated in Fig. 7, a distance sufficient to interfere with the bar of the form illustrated in Figs. 1, 2 and 3. 40 The section 33 of the bar of the modified construction illustrated in Figs. 6, 7 and 8 is of a length ample to pass around the deepest type of window casing and therefore can be used in certain environments where 45

the form shown in Figs. 1, 2 and 3 could 50 not be used.

In Figs. 4 and 5 I have shown a form of clasp for engagement with the head 12 and comprising a vertically slotted body part 40 with spring latch 41 to engage the upper 55 head 12 of the anchor when the slotted portion of the bar 40 is slid over the anchor projection. From the lower end of the body part projects a rope fastener 42 provided with a pair of holes 43, 44 positioned one 60 above the other and arranged to receive and form a half hitch in the rope. The rope indicated in Fig. 1 passes in the lower course 45 up through the lower hole 44 and then bends over, as at 46, and passes on through 65 the upper hole 43. A bend of rope is then brought over one side and through the loop part 46, as at 48. This tie or half hitch forms an easily shifted connection between the rope and the clasp, the operator being 70 able with one hand to loosen it and shift it from one point to another along the rope.

Whereas I have illustrated and described but two embodiments of my invention it is 75 possible that many changes and modifications may be made therein without departing from the spirit thereof or the scope of the appended claim.

Having described my invention, what I 80 claim is:

An anchor for attachment to the reveal in a brick wall between the face of the wall and a window casing, comprising a vertically elongated base to lie against the reveal, a pair of headed projections extending 85 outwardly from the upper and lower portions of the base, and a flat anchor bar extending from the rear of the base to lie between adjacent courses of brick, said bar extending away from the reveal to project 90 beyond the outer edge of the casing and its end portion extending away from the face of the wall to a point inside the second layer of brick.

In testimony whereof I hereunto set my 95 hand.

GEORGE F. MINNIS.
